UNITED STATES PATENT OFFICE.

THOMAS BENTON DORAN AND NATHANIEL MARCUS SHINN, OF PHILADELPHIA, PENNSYLVANIA, ASSIGNORS TO SAID DORAN AND ROBERT DORAN, OF PHILADELPHIA, PENNSYLVANIA, COMPOSING THE FIRM OF DORAN BROTHERS.

PILE-FABRIC LOOM.

No. 831,045.

Specification of Letters Patent.

Patented Sept. 18, 1906.

Application filed August 30, 1905. Serial No. 276,352.

To all whom it may concern:

Be it known that we, THOMAS BENTON DORAN and NATHANIEL MARCUS SHINN, citizens of the United States, residing at Philadelphia, in the county of Philadelphia and State of Pennsylvania, have invented certain new and useful Improvements in Pile-Fabric Looms, of which the following is a specification, reference being had therein to the accompanying drawings, forming a part thereof.

Our invention relates to warp-crossing mechanism for crossing pile-warp threads over longitudinal pile-wires, and has for its objects simplicity of construction, ease of insertion of warp-threads, permanency of adjustment and durability, ease of operation, and certainty and reliability of operation.

Our invention obviates the use of additional reeds or combs, such as have heretofore been employed to effect this crossing operation and which have provided one or more additional parts through which the warp-threads must be inserted in placing them in the loom, and our invention provides pile-warp deflectors of strong and simple construction, combined with pile-wires which may be of ordinary construction to positively effect the crossing operation with the expenditure of slight power.

We will now describe the constructions embodying our invention illustrated in the accompanying drawings and will thereafter point out our invention in claims.

Figure 1 is a longitudinal vertical section showing parts of a loom embodying our invention. Fig. 2 is a detail rear end elevation of the pile-wires, pile-warp deflectors, adjacent parts, and operating mechanism with the pile-warp deflectors moved to the left extreme position. Fig. 3 is a similar view, omitting the operating cam and lever, with the pile-warp deflectors moved to the right extreme position. Fig. 4 is an enlarged end elevation, and Fig. 5 an enlarged side elevation, of a portion of a pile-warp deflector of modified construction.

The drawings illustrate only such parts of the loom as are required for an understanding of the present invention.

The lay 1 is of ordinary construction and only its upper portion, including the reed 2, is shown, and it is shown in extreme forward

position, at which position the lift of the pile-warp selected to form the pile will occur in the weaving of a fabric such as shown in the 55 loom in Fig. 1.

The pile-wires are shown as of ordinary construction and are clamped at their front ends upon a stationary cross-bar 23 by means of a clamping-plate 24, held down by screws 60 25. Each pile-wire has a horizontally-extending portion 3, having a stationary knife 4 set therein, and has an upwardly and rearwardly inclined portion 5 in rear of the horizontal portion and also has an upright portion 6, forming the extreme rear portion of each pile-wire. These rear upright portions at their lower ends enter vertical grooves in a stationary cross-bar 7, this stationary cross-bar being carried by an angle-beam 8 in the 7c usual manner.

The pile-warp deflectors embodying the present invention are shown as secured at their lower ends to the vertical portions of the pile-wires just above the cross-bar 7, this 75 construction being simple and obviating the formation of additional grooves in the cross-bar for the pile-warp deflectors. Each pile-warp deflector consists of an upright strip 9, preferably of flat metal, as shown, secured at 80 its lower end, as aforesaid, to the lower part of the upright portion of the pile-wire and extending upward in substantial parallelism to the upright portion of the pile-wire, but extending a considerable distance above the 85 pile-wire and entering vertical slots in a movable cross-bar 10, which is fitted to slide transversely of the loom. Each pile-warp deflector 9 is provided with laterally-extending 90 projections 11, adapted to extend over each adjacent pile-wire, and these projections are shown as formed so that they will closely overlie the pile-wires and have slightly-rounded corners at their lower portions, so as not to catch the warp-threads when the 95 warp-threads are lifted, and have easy inclinations from their upper to their lower portions, so as to form guiding-surfaces for the warp-threads as the warp-threads are lowered, these guiding-surfaces performing the 100 function of guiding the warp-threads from one side to the other of each pile-wire as the warp-threads are lowered.

In Fig. 2 the pile-warp deflectors are

shown in their extreme position to the left, and while they are in this position the warp *e*, which is to form the pile, will be lifted and will pass freely upward without obstruction 5 to a position above the pile-wires, as shown in Fig. 1. In Fig. 3 the pile-warp deflectors are shown after they have been moved to their extreme positions to the right and the parts are now in position to guide the pile-warp in its downward movement, so as to 10 loop the warp over the pile-wires. Here also, it will be noted, there is no obstruction to the downward movement of the warps. The lower position of the pile-warp is shown by 15 broken lines *e'* in Fig. 1. This position will be maintained until the shuttle has been thrown and the lay has beaten up the weft and until the warp to form the pile has been again lifted. The pile-warp deflectors will 20 then be shifted to the left and the pile-warp will be lowered and guided by the pile-warp deflectors, so as to be looped back over the pile-wires. The shuttle will then be thrown and the weft beaten up. Thus the pile-warp 25 will be positively guided and deflected through guideways of ample width for its free movement.

The movable cross-bar 10 is shown as slidably connected by screws 12, entering slots 30 13 in the movable cross-bar, to studs 14, secured to the upper angle-beam 15 of the loom. A connecting-rod 22 joins this movable cross-bar to an actuating-lever 16, which is pivoted at 20 and is controlled by a cam 35 17, the actuating-lever being provided with a cam-roller 18, working against the periphery of the cam and held against the cam by the spring 19. A cam-shaft 21 is suitably geared so as to make one-half a revolution for each 40 beat of the lay, and, as shown in Fig. 2, the cam is about to shift the pile-warp deflectors from the left to the right.

The upper ends of the pile-warp deflectors 9 enter freely and loosely into the slots provided for them in the movable cross-bar 10, and their movement is effected by slight flexure thereof in an upright plane transverse to the loom, the amount of movement being small and requiring the expenditure of 45 but slight power.

The other warp-threads of the fabric are shown in proper positions in Fig. 1, the drag and stuffer warps *d* being indicated by a single line and the binder warp-threads *a* and *b* being also shown.

In the construction of pile-warp controller above described the projections 11 are shown as formed by a thickening of the material of the warp-controllers which may be effected 60 by suitable solder. In the modified construction shown in Figs. 4 and 5 these projections 26 are shown as formed by obliquely twisting the warp-deflectors with a comparatively sharp twist at the lower portions of 65 each projection and a comparatively easy

twist at the upper portion thereof. Obviously the operation of both constructions is the same.

It will be noted that the projections on the pile-warp deflector perform the function of 70 guiding or deflecting the pile-warp threads during the downward movement of the pile-warp threads as above described and may therefore properly be termed "deflector" projections. It will also be noted that each 75 pile-warp deflector intermediate of the pile-wires provides two deflector projections, one for each adjacent pile-wire, and that each pile-wire has two deflector projections co-operative with the pile-wire to deflect the pile- 80 warp thread to one or the other side of the pile-wire.

It is obvious that various modifications may be made in the constructions shown and above particularly described within the principle and scope of our invention.

What we claim, and desire to secure by Letters Patent, is—

1. The combination, with two longitudinal pile-wires, of a movable pile-warp deflector 90 of such length as to include the full extent of the upward and downward movement of the pile-forming threads at their intersections with a plane extending transversely of the loom and passing through the pile-warp deflector provided with two deflector projections, one for each pile-wire and each arranged to overlie its respective pile-wire in one position of the pile-warp deflector, and means for actuating the pile-warp deflector. 100

2. The combination, with longitudinal pile-wires, of movable pile-warp deflectors, each of such length as to include the full extent of the upward and downward movement of the pile-forming threads at their intersections with a plane extending transversely of the loom and passing through the pile-warp deflector and each pile-warp deflector having two deflector projections, one deflector projection being arranged to overlie one of the adjacent pile-wires in one position of the pile-warp deflector and the other deflector projection being arranged to overlie the other adjacent pile-wire in another position of the pile-warp deflector, and means 110 for actuating the pile-warp deflectors. 115

3. The combination, with a longitudinal pile-wire, of two pile-warp deflectors movable by flexure thereof, each pile-warp deflector having a deflector projection arranged to 120 coact with the pile-wire in one position of the pile-warp deflector, and means for actuating the pile-warp deflectors.

4. The combination, with longitudinal pile-wires, of pile-warp deflectors movable by 125 flexure thereof, the pile-warp deflectors having deflector projections, and means for actuating the pile-warp deflectors.

5. The combination, with a longitudinal pile-wire, of two pile-warp deflectors, each 130

pile-warp deflector being stationarily held at its lower end and movably controlled at its upper end and having a deflector projection arranged to coact with the pile-wire in one position of the pile-warp deflector, and means for actuating the pile-warp deflectors at their upper ends.

6. The combination, with longitudinal pile-wires, of movable pile-warp deflectors 10 stationarily held at their lower ends and movably controlled at their upper ends and having deflector projections, and means for actuating the pile-warp deflectors at their upper ends.

15 7. The combination, with a longitudinal pile-wire, of a pile-warp deflector movable in an upright plane extending transversely of the loom and of such length as to include the full extent of the upward and downward movements of the pile-forming threads at their intersections with such plane and having a deflector projection thereon, and means for actuating the pile-warp deflector.

20 8. The combination, with a longitudinal pile-wire, of two pile-warp deflectors, one at each side of the pile-wire, each pile-warp deflector being movable in an upright plane extending transversely of the loom and of such length as to include the full extent of the upward and downward movements of 25 the pile-forming threads at their intersections with such plane and having a deflector projection arranged to coact with the pile-wire in one position of the pile-warp deflector, and means for actuating the pile-warp deflectors.

30 9. The combination, with longitudinal pile-wires, of pile-warp deflectors movable in a common upright plane extending transversely of the loom and of such length as to 35 include the full extent of the upward and downward movements of the pile-forming threads at their intersections with such plane and having deflector projections thereon arranged to coact with the pile-wires, and means for actuating the pile-warp deflectors.

40 10. The combination with two longitudinal pile-wires, each having an upright rear portion, of a movable pile-warp deflector arranged between and in substantially the same plane transversely of the loom as the 45 upright rear portions of the pile-wires and of such length as to include the full extent of the upward and downward movements of the pile-forming threads at their intersections with such plane and provided with two 50 deflector projections, one for each pile-wire and each arranged to overlie its respective pile-wire in one position of the pile-warp deflector, and means for actuating the pile-warp deflector.

55 11. The combination, with longitudinal pile-wires having upright rear portions, of movable pile-warp deflectors arranged between and in substantially the same plane 60 transversely of the loom as the upright rear

portions of the pile-wires, and of such length as to include the full extent of the upward and downward movements of the pile-forming threads at their intersections with such plane each pile-warp deflector having two 70 deflector projections, one deflector projection being arranged to overlie one of the adjacent pile-wires in one position of the pile-warp deflector and the other deflector projection being arranged to overlie the other 75 adjacent pile-wire in another position of the pile-warp deflector, and means for actuating the pile-warp deflectors.

12. The combination, with a longitudinal pile-wire having an upright rear portion, of 80 two pile-warp deflectors movable by flexure thereof and arranged at each side of and substantially in the same plane transversely of the loom as the upright rear portion of the pile-wire and provided with deflector projections, and means for actuating the pile-warp deflectors.

13. The combination, with longitudinal pile-wires having upright rear portions, of 85 pile-warp deflectors movable by flexure thereof and arranged between and in substantially the same plane transversely of the loom as the upright rear portions of the pile-wires and having deflector projections, and means for actuating the pile-warp deflectors. 95

14. The combination, with a longitudinal pile-wire having an upright rear portion, of 100 two pile-warp deflectors arranged one at each side of and both in substantially the same plane transversely of the loom as such 100 upright rear portion of the pile-wire and each pile-warp deflector being stationarily held at its lower end and movably controlled at its upper end and movable in an upright transverse plane and having a deflector projection arranged to coact with the pile-wire in one position of the pile-warp deflector, and means for actuating the pile-warp deflectors 105 at their upper ends.

15. The combination, with longitudinal 110 pile-wires having upright rear portions, of pile-warp deflectors arranged between and in substantially the same plane transversely of the loom as the upright rear portions of the pile-wires and stationarily held at their 115 lower ends and movably controlled at their upper ends and movable in said upright transverse plane and having deflector projections, and means for actuating the pile-warp deflectors at their upper ends. 120

16. The combination, with two longitudinal pile-wires each having an upright rear portion, of a movable pile-warp deflector arranged between and in substantially the same plane transversely of the loom as the 125 upright rear portions of the pile-wires and stationarily held at its lower end and movably controlled at its upper end and movable in said upright transverse plane and having two deflector projections, one for 130

each pile-wire and each arranged to overlie its respective pile-wire in one position of the pile-warp deflector, and means for actuating the pile-warp deflector at its upper end, substantially as set forth.

17. The combination, with longitudinal pile-wires having upright rear portions, of pile-warp deflectors arranged between and in substantially the same plane transversely of the loom as the upright rear portions of the pile-wires and stationarily held at their lower ends and movably controlled at their upper ends and movable in said upright transverse plane, each pile-warp deflector having two deflector projections, one deflector projec-

tion being arranged to overlie one of the adjacent pile-wires in one position of the pile-warp deflector and the other deflector projection being arranged to overlie the other adjacent pile-wire in another position of the pile-warp deflector, and means for actuating the pile-warp deflectors at their upper ends, substantially as set forth.

In testimony whereof we have affixed our signatures in presence of two witnesses.

THOMAS BENTON DORNAN.
NATHANIEL MARCUS SHINN.
